DESIGN FOR A KNIFE RACK

Henry Peter Glass, Chicago, Ill., assignor to Eko Products Company, Chicago, Ill., a corporation of Illinois

Application August 12, 1944, Serial No. 114,865

Term of patent 14 years

(Cl. D44—29)

To all whom it may concern:

Be it known that I, Henry Peter Glass, a citizen of the United States, residing at Chicago, in the county of Cook and State of Illinois, have invented a new, original, and ornamental Design for a Knife Rack, of which the following is a specification, reference being had to the accompanying drawing forming part thereof.

Fig. 1 is a front perspective view of a knife rack, showing my new design.

Fig. 2 is a reduced edge elevational view of the same.

Fig. 3 is a reduced front elevational view of the same.

I claim:

The ornamental design for a knife rack, as shown.

HENRY PETER GLASS.
